Attorney.

UNITED STATES PATENT OFFICE.

EDWIN W. COCHRAN, OF CATAWBA, NORTH CAROLINA.

WRENCH.

1,368,900.

Specification of Letters Patent. Patented Feb. 15, 1921.

Application filed June 3, 1919. Serial No. 301,411.

To all whom it may concern:

Be it known that I, EDWIN W. COCHRAN, a citizen of the United States, residing at Catawba, in the county of Catawba and 5 State of North Carolina, have invented certain new and useful Improvements in Wrenches; and I do hereby declare the following to be a full, clear, and exact description of the invention, such as will enable 10 others skilled in the art to which it appertains to make and use the same.

This invention relates to wrenches and the primary object of the invention is to provide an improved means for adjusting 15 the jaws so that the same can be quickly moved and held in such position.

A further object of the invention is to provide a quick adjusting wrench which can be operated with one hand thus making 20 the wrench particularly adapted for use in close quarters.

A further object of the invention is to provide an adjusting piece slidably mounted in the handle of the wrench so that the same 25 can be conveniently and easily operated.

A still further object of the invention is to provide an improved wrench of the above character, which is durable and efficient in use, one that is simple and easy to manufacture, and one that can be placed upon the 30 market at a reasonable cost.

With these and other objects in view, the invention consists in the novel construction, arrangement and formation of parts, as will 35 be hereinafter more specifically described, claimed and illustrated in the accompanying drawings forming a part thereof in which:

Figure 1 is a plan view of the improved wrench,

40 Fig. 2 is a similar view, showing the cover plate removed,

Fig. 3 is a longitudinal section through the improved wrench taken on the line 3—3 of Fig. 1,

45 Fig. 4 is a detail transverse section taken on the line 4—4 of Fig. 1,

Fig. 5 is a detail transverse section taken on the line 5—5 of Fig. 1,

Fig. 6 is a detail perspective view of one 50 of the jaws removed from the wrench, and

Fig. 7 is a detail perspective view of the adjusting slide and head removed from the wrench.

Referring to the drawings in detail, 55 wherein similar reference characters designate corresponding parts throughout the

several views, the numeral 1 generally indicates the improved wrench, which includes the open frame or body 2 having its rear end enlarged to form a handle 3. The side edges 60 of the handle 3 are serrated or milled, as at 4, so that a firm grip may be obtained on the same. The forward end of the frame 2 is provided with the head 5 which projects beyond the sides of the frame and extends at 65 an angle of substantially twenty-two degrees thereto. The opposite sides of the head 5 are provided with grooves 6 for the reception of ribs 7 formed on the jaws 8 and 9, which are identical in shape and size. 70 The free forward edges of the head 5 are beveled forwardly in opposite directions and form a substantially arrow-shaped extension 10, which forms means for retaining the jaws against forward movement. The frame 75 2 has the inner walls thereof cut away from the central portion thereof toward its forward end to define a pair of shoulders 12 and a guide for the head 13 of the adjusting slide 14.

The adjusting slide 14 is provided with the rearwardly extending shank 15 which is slidably received between the inner walls of the handle and the rear end of the shank and is provided with a thumb piece 16, 80 whereby the same may be readily adjusted. The side edges of the thumb piece 16 are provided with grooves 17 for the reception of the inwardly extending ribs 18 formed on the inner walls of the handle. The ribs 18 form a guide track for the thumb piece 85 and prevent relative lateral movement thereof in relation to the handle. The thumb piece 16 has its outer surface serrated so as to prevent the thumb from slipping thereon 90 while the same is being adjusted.

Each of the jaws 8 and 9 includes a body 19 having the rib 7 formed on the inner face thereof, which is slidably fitted in the groove 6, as stated, and the lower surface 100 of the body has secured thereto the downwardly extending shank 20, which is secured adjacent one end of the body and extends at an angle thereto in a direction toward the opposite end of the body. The 105 body also has its inner face directly above the rib 7 beveled inwardly and downwardly, as at 21, for receiving the arrow-shaped extension 10 of the head 5. The outer edge of the body has the upwardly extending 110 jaw proper 22 formed thereon which is positioned at the opposite end of the body

from the shank 20 and the same is formed relatively thick and overhangs the arrow-shaped extension 10 of the head 5 and slidably engages the upper outer edge of the 5 body of the opposite jaw.

The head 13 of the adjusting slide 14 is provided with longitudinally extending grooves 23 which extend diagonally across the faces of the head 13 in opposite directions and these grooves slidably receive the shanks 20 of the jaws 8 and 9.

As clearly shown in Fig. 2 of the drawings, the shanks of the jaws 8 and 9 extend diagonally and inwardly in opposite 15 directions, and cross each other at the point of connection with the head 13 of the adjusting slide.

Upon movement of the thumb piece 16, the adjusting slide will be moved accordingly and thus the jaws adjusted toward or away from each other according to the direction in which the slide is moved.

Cover plates 24 are provided, so as to house the head of the adjusting slide and 25 the shanks 20 of the jaws so as to absolutely hold the same against displacement and the outer surfaces of the frame are suitably recessed so as to receive the cover plate so that the same will extend flush with the 30 outer surface of the frame. The inner edges of the outer faces of the jaws are also provided with grooves 25 for receiving the outer ends of the cover plate and the cover plate serves to strengthen the jaws 35 so as to prevent breakage thereof and to prevent outward movement of the same in relation to each other. The cover plates are held in position by suitable fastening elements 26 which extend through the plates 40 and into the frame.

From the foregoing description, it can be seen that an improved quick adjusting wrench is provided which can be readily

operated with one hand and in which the jaws are firmly held against movement during operation thereof.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, 55 proportion and arrangement of parts may be resorted to, when required without sacrificing any of the advantages of my invention as set forth.

What I claim as new is:

A wrench including a body having a head formed on one end thereof, the head having a guide extending transversely across the median longitudinal dimension of the body and disposed at an acute angle 65 thereto, grooves formed in the opposite faces of said head, jaws slidably mounted on said head for movement transversely of said body provided with diagonally extending disposed shanks, ribs formed on said 70 jaws and slidably engaging said grooves, a longitudinally extending adjusting member, a head on the outer end of said adjusting member, said head having oppositely directed inclined grooves formed in the 75 faces thereof, said inwardly extending diagonally disposed shanks slidably received in the grooves formed in the head of the adjusting member, as and for the purpose specified.

In testimony whereof I affix my signature in presence of two witnesses.

EDWIN W. COCHRAN.
